UNITED STATES PATENT OFFICE.

GEORGE D. BARNARD, OF ST. LOUIS, MISSOURI.

BOOK.

SPECIFICATION forming part of Letters Patent No. 399,469, dated March 12, 1889.

Application filed March 2, 1888. Serial No. 265,973. (No model.)

To all whom it may concern:

Be it known that I, GEORGE D. BARNARD, of St. Louis, Missouri, have made a new and useful Improvement in Books, of which the following is a full, clear, and exact description.

The improvement relates to that class of books in which the signatures are attached to guards or strips, which in turn are attached to whatever constitutes the book-back. The improvement consists in the special manner of constructing the guard or strip and attaching it to the signature and back, substantially as is hereinafter described and claimed, and as illustrated in the annexed drawings, making part of this specification, in which—

Figure 1 is a view in perspective showing a signature attached to a guard; Fig. 2, an end elevation of the same. Fig. 3 is a view in perspective showing signatures attached to their respective guards, the guards in turn being attached to each other and a back-strap being attached to the guards; Fig. 4, an end elevation of the parts of Fig. 3; Fig. 5, an end elevation showing all the guards in position and attached together and to the back-strap and some of the signatures attached to their guards; and Fig. 6 is a view looking toward the rear of the back-strap and showing the mode of attaching it to the guards.

The same letters of reference denote the same parts.

The book-cover, as well as other parts not essential to an understanding of the improvement, are not shown.

A, Figs. 1 and 2, represents a signature of the book.

B represents the improved guard. It is, when in position—that is, when its inner edge is attached to the back-straps and its outer edge to the signature—a stiff strip interposed between the leaves and the back, and serving, when the book is opened, to raise the inner edge of the signature and form a bearing upon which the signature, or any of the leaves of the signature, can turn. It is composed in practice of any suitable material, such as cloth stiffened either by employing a number of folds of the cloth, or by combining paper or pasteboard with cloth, or by treating the cloth with some cement

calculated to give body to it. To enable the signature to be hinged to the outer edge of the guard, it (the guard) is made to open at its inner edge, b, and the signature is attached by sewing it to the middle of the opened guard, substantially as shown at C, Figs. 1 and 2. The guard is attached to the back, which is composed of straps—such as D, Figs. 3, 4, 5, and 6—by closing its folds b' b² and sewing them together and to the straps, as follows: In each fold of the guard is a series of perforations, b³, the perforations in one of the folds being respectively opposite those in the other of the folds. The fold b' of one signature-guard is attached to the fold b² of the adjoining signature-guard by sewing, E, Figs. 3 and 4. The adjoining guards are similarly united, the sewing E being passed through the perforations b³. The same stitching E is, as each guard is joined to the preceding guard, carried around the strap D, as shown in Figs. 3, 4, and 5, and the guards are finally united to the back-straps, as shown in Fig. 5. These perforations b³ greatly facilitate and cheapen the operation of uniting the guards to each other and to the straps, and they also serve to direct the lines of stitching, so that said lines shall come opposite each other in the two folds of a guard, and also in all the guards when assembled in the book, thereby enabling the book-leaves to be held to better advantage and to be opened more uniformly and the signatures to be more readily registered; and after once adjusted vertically to be more firmly held in place.

I desire to state that I do not in this application claim the subject-matter described and claimed in a pending application of mine for Letters Patent for an improvement in books, Serial No. 247,464, filed August 20, 1887; nor do I claim the subject-matter described and claimed in Letters Patent No. 392,840, issued to me November 13, 1888, for an improvement in books.

I claim—

1. The herein-described book-guards, the same consisting of a strip folded, stiffened, and perforated, as set forth.
2. The combination of the straps, the guards, and the signatures, said guards being perforated and the guards connected with

each other and with the straps, substantially as described.

3. The combination of the straps, the guards, and the signatures, said guards being 5 folded, stiffened, and perforated, and the guards being connected with each other and with the straps, substantially as described.

Witness my hand this 28th day of Febru- 10
ary, 1888.

GEO. D. BARNARD.
